SLIP COVER FOR SEAT CUSHIONS

Isaac A. Evans, Muncie, Ind.

Application February 6, 1947, Serial No. 726,746

2 Claims. (Cl. 155—182)

1

On account of the severe wear to which the surfaces of the automobile seat cushion is subjected, there has long been the need of an auxiliary or slip cover for said surfaces, a cover that would be durable, easy to apply, neat in appearance and form fitting, and resistive of tendencies to become wrinkled, distorted, or displaced.

Qualities desired in such proposed new cover are that besides being so constructed that it is capable of being applied to close adherence with said cushion, and of being of form to fit neatly not only to the top surface but also the front, the back, and the ends of the cushion, it must be so designed as to be susceptible to the practice of standardized production methods, and of being economical of manufacture.

To provide a cover affording the above named advantages, and also to provide a method and procedure of making same which is capable of being practiced by a person of ordinary skill, and which said method lends itself to a considerable saving of time and material is the object, broadly stated, of my invention.

The said general object, as well as other and more specific aims which will presently appear, are accomplished by the new construction, combination and arrangement of parts, and by the several transactions of which my new method of manufacture consists, are described and explained in the following specification, and illustrated in the accompanying drawings.

In the drawings—

Figure 1 is a plan view of a quota of textile fabric fashioned to conformation for constituting, as it does, the body piece of my new slip cover. The broken lines appearing in this view are to be referred to in the description of procedure of making the cover.

Figure 2 is a detail view of the curves and angles that are involved in the opposed frontal upper corners of the top portion of the cover, and of the forward portions of the side wall portions of the cover.

Figure 3 shows the conformation of the left hand wall piece.

Figure 4 shows the conformation of the right hand wall piece.

Figure 5 is a front view indicating the appearance of the new cover applied to a cushion of the class hereinbefore mentioned, and before the free bottom marginal portions of the cover will have been turned inwardly.

Figure 6 is an end view, in the direction of arrow 6 in Figure 5.

Figure 7 is a front view illustrative of an automobile seat cushion of conventional form and proportions selected as being suitable for the purpose of showing a typical application of my invention.

Figure 8 is a top plan view of the view shown in Figure 7.

2

Figure 9 is an end view, in the direction of arrow 9 in Figure 8.

Figure 10 is a perspective view indicating the appearance of my new cover applied to the cushion, and after the bottom marginal portions have been turned and fastened to the underside of the frame of the cushion.

Figure 11 is a perspective view showing the appearance of the new cover as indicated in Figure 10 the cushion being inverted.

Referring now to the typical cushion, as in Figures 7, 8 and 9. The angle of incline each, of the front wall A, and back wall B, is approximately seven and one half degrees from the perpendicular of the base of the cushion. The curvature of the quadrantal corners C each, of the frontal portion of the top surface of said cushion is of an arc of ninety degrees. The interior structure of the cushion comprises the usual frame, and the springs and padding (not shown) imparting to the cushion the usual yieldability and resiliency.

From the stock of textile fabric, as leatherette, tapestry, herringbone and the like, is cut a body piece quadrilateral in formation and of predetermined length and width L and W respectively. Main portion 11 between parallel demarcations 12 and 14 is of outline corresponding to the outline of the top surface of the said cushion. Portion 16 between the demarcations 12 and 17 is of the dimensions corresponding to the length and height of the back wall B of said cushion. Portion 18 between the demarcations 14 and 19 is of dimensions corresponding to the length and height of the front wall A of the said cushion. The conformation of each of the extremities of the said front portion 18, is of a reversed curve consisting of the convex arc 21 of radius same as radius of curve C of said cushion and concave arc 22, and of a tangent 24 which extends from said arc 22 at an acute angle F to demarcation line 14 and through the marginal portion thereat.

G designates a broken straight line on which the centers of said arcs 21 and 22 are located. It is inclined at an angle Q to the perpendicular Q' drawn through center of arc 21 to demarcation line 14. The point M of tangency of said arcs is coincident with said demarcation line 14.

End wall pieces 26 and 26 being similar in conformation and dimensions (one being designated L as indicating left hand, and the other being designated R indicating right hand) same are described in singular. Each has its rear end H of height same in dimension as the width of the back wall portion 16 of said body piece. The forward extremity of said wall piece is of the formation of an arc 27 and of a tangent 28 which extends from said arc at an inclination from the top edge 29 of said wall piece at an angle P which is the same in degree as angle K (see

Figure 2). The said upper edge 29 is of length equivalent to the distance marked O on the main portion of the said body sheet plus the curve of arc 21 and to the point of tangency M.

The external broken border lines adjacent to boundary lines of the top and ends of said end wall pieces, and the ends of the main portion 11 of the body piece and of the ends of side portions thereof 16 and 18 respectively, indicate the borders to be lain together for stitching.

The transaction of combining the said body piece and the said end wall pieces, consists of laying one of the said end wall pieces (as indicated by the broken lines in Figure 1) in position with the borders of forward edges 28-27 in side by side arrangement with the edges 24-22 of the body piece, cord welt or its equivalent (not shown) being interposed between the opposed faces of said edges. Stitching by machine then proceeds, and as point M is reached, the edge 29 of the end wall piece is rolled on the arc 21 and along the edge 15 of the main portion of the body piece, stitching proceeding at the same time and thence along the edge 23 of the back portion 16 of the body piece and the edge H of the rear end of said end wall piece. The procedure of securing the other end wall piece to the opposite end of the body sheet is the same as above described. The stitching operation may start either at the end edges H-23, or the frontal edges 28-24. With the combining of both of the end wall pieces to the body piece, as above described, the cover will have been completed.

The marginal portions 34 and 35 of the body piece, and the marginal portions 36 of the end wall pieces provide flaps, slitted as at 37 and 39, are adapted to be turned inwardly and fastened in suitable manner as by hog rings or cords to the bottom of the cushion frame if of metal or wire, or by tacks, if the frame is of wood.

The construction accomplished as above described constitutes a cover composed of a minimum number of pieces, is substantial, close fitting and of neat appearance and by reason of its corner contours constructed and arranged as described, the inherent quality of resiliency residing in the cushion is made to contribute to the close fitting and firm union with the cushion surfaces. Adaptation of the invention in manufacturing procedures involves modifications only that are incident to angles of inclination which depart materially from the conventional angles dealt with in the embodiment of my invention as it is herein described and illustrated.

Applying my new cover consists simply in placing the front portion 18 and the main portion 11 of the cover upon the front wall A and top surface respectively, of the cushion. Then, by bearing down on the cambered surface of the cushion and hooking a corner of the end portion of the back portion 16 over a rear corner of the cushion, and by working the mid. portion rearwardly and working the said back portion 16 downwardly the other end portion of said back portion is readily hooked over the remaining corner of the cushion. By then drawing and working down the front, back and end portions, same together with the mid or main portion of the cover will have come to immediate and adhering union with the surfaces of the cushion, the tautness of said union being contributed to by the upward bulge of the top surface of the cushion.

Securing the marginal bottom portions of flaps

on the said cover consists in turning them inwardly and then fastening same in suitable manner to the under part or parts of the frame.

Experience with my invention, having proved that the stretching incident to applying the cover is inconsiderable, the making of same to close dimensions and contours as described is practicable.

It will be understood that minor modifications may be made, within the scope of the invention as it is defined in the claims, without departing from the spirit or principle of the invention or sacrificing any of its advantages.

What I claim as my invention is—

1. A slip cover of the kind described, consisting of a body piece of textile material quadrilateral in conformation and of predetermined length, the main part thereof being of predetermined width and its opposed parallel side portions each being of predetermined width, one of said side portions being greater in width than the other, the frontal corner portion of said main part and the adjacent side edges of the wider of said side portions being of the conformation of a reversed curve having arcs with acute central angles, and of a tangent extending from the concave arc of said curve, the mutual point of tangency of said arcs coinciding with the line of juncture of said main part and the wider side portion of said body piece, and wall pieces trapezoidal in shape each having one of its end edges equal to the width of the narrower side portion of said body piece, and having a top edge equal in length to the sum of the lengths of the side edge of the main part of said body piece and the edge of the convex arc of said reversed curve, and the other of its end edges of the same conformation as the aforesaid concave arc and tangent, the said end edges and top edge of each of said end wall pieces being bound to a side edge of said body piece.

2. A slip cover for an automobile cushion quadrilateral in plan and trapezium shaped in cross section, consisting of a body piece of textile material the main portion thereof being of conformation to correspond with the conformation of the top surface of the cushion, and its opposed parallel side portions being of predetermined width, one to correspond with the height of the back, and the other to correspond with the height of the front side, of the said cushion, the frontal corner portions of said main portion and the adjacent side edges of the front side portion of said body piece being of the conformation of a reversed curve having arcs with acute central angles, and of a tangent extending from the concave arc of said curve, the mutual point of tangency of said arcs coinciding with the line of juncture of said main portion and said front side portion of the body piece; end wall pieces trapezoidal in shape each having a rear edge equal to the height of the rear side of said cushion, a top edge equal in length to the sum of the lengths of the side edge of said main portion and the edge of the convex arc of the said reversed curve, and a front edge of the same conformation as the aforesaid concave arc and tangent, the said rear edge, top edge and front edge of each of said end wall pieces being sewn to a side edge of said body piece.

ISAAC A. EVANS.
